Primary Examiner — Catherine Tuttle(74) Attorney, Agent, or Firm — B. Aaron Schulman, Esq.; Stites & Harbison, PLLC(57) CLAIM

The ornamental design for a flask with cap, as shown and described.

DESCRIPTION

FIG. 1 is a perspective view showing our new design for a flask with cap;

FIG. 2 is a front view thereof;

FIG. 3 is a back view thereof;

FIG. 4 is a side view thereof;

FIG. 5 is a top view thereof; and,

FIG. 6 is a bottom view thereof.

The broken lines are included for the purpose of illustrating portions of the flask with cap that form no part of the claimed design.
